UNITED STATES PATENT OFFICE.

WILLIAM A. FAIRBURN, OF SHORT HILLS, NEW JERSEY, ASSIGNOR TO THE DIAMOND
MATCH COMPANY, OF CHICAGO, ILLINOIS, A CORPORATION OF ILLINOIS.

PROCESS OF TREATING MATCH-SPLINTS.

1,070,024.

Specification of Letters Patent. Patented Aug. 12, 1913.

No Drawing.

Application filed October 28, 1912. Serial No. 728,079.

To all whom it may concern:

Be it known that I, WILLIAM A. FAIRBURN, a citizen of the United States, and resident of Short Hills, in the county of 5 Essex and State of New Jersey, have invented certain new and useful Improvements in Processes of Treating Match-Splints, of which the following is a specification.

10 The object of this invention is to provide a process of treating match splints whereby the splints are economically and efficiently impregnated with flame-carrying and non-glowing agents, the former serving as a 15 vehicle to transmit the flame from the match-head composition to the body of the splints and the latter agent rendering the splints non-glowing when the flame is extinguished.

In carrying out my invention I provide a 20 liquid bath comprising at least two superimposed immiscible liquids of different specific gravity, into which the match splints are dipped to a sufficient depth and for a sufficient period until the splints are properly 25 impregnated with the constituents of the liquids. The properties of these liquids are such that one provides or serves as a vehicle to transmit the flame from the ignition head-composition of the match to the 30 body of the splint, and the other liquid provides or serves as an incombustible agent to render the splint non-glowing after the flame has been ignited and extinguished.

35 Preferably the sub-liquid is a flaming agent comprising an organic oil which is insoluble in an alcohol, and the super-liquid is an alcoholic solution of a non-combustible substance, such solution being of less specific gravity than the oil and thus floating upon 40 the top of the latter.

Efficient results are attainable by the use, for example, of cotton seed oil as the flaming agent, and a two per cent. solution of boric acid in methyl alcohol as the non-glowing 45 agent. Splints subjected to this bath dry readily; they are not greasy; they are very inflammable, and they are well impregnated with the non-glowing material.

In pursuance of my invention, the oil is 50 poured into a suitable tank, and the alcoholic solution is then floated on the oil, the depths of the respective liquids being such as to permit the dipping of the splints vertically to a substantial extent in both liquids.

Ordinarily a layer about one-half inch deep 55 of the alcoholic solution will suffice; the depth of the sub-stratum of oil being such that vertically-disposed splints may be dipped thereinto about one-half inch.

When my invention is used in connection 60 with the manufacture of matches upon a continuous match making machine of the type wherein the splints are inserted row by row in an endless carrier and thereby held in spaced relation to each other and transported through the match-making path, the 65 tank containing the superimposed liquids is suitably located beneath the route of the carrier, so that the depending splints on the latter during their travel toward the head- 70 composition applying devices can be dipped into and subjected to the action of the bath until the efficient impregnation of the splints with the respective components of the bath 75 shall have been attained.

I do not limit myself to the use of the specific liquids herein described nor to the specific relation of one liquid to the other; as my invention, in its broad aspect, contemplates the use of any superimposed immiscible liquids of different specific gravity which respectively impart to the splints 80 dipped therein the flaming and non-glowing characteristics hereinbefore mentioned.

I claim—

1. The process of treating match splints which consists in subjecting the splints to a bath comprising superimposed immiscible liquids of different specific gravity, the properties of the liquids being such that one 90 serves as a flame-carrier and the other as a non-glowing agent for the splints.

2. The process of treating match splints which consists in subjecting the splints to a bath comprising superimposed immiscible liquids of different specific gravity, the properties of these liquids being such that the lower liquid serves as a flame carrier and the upper liquid as a non-glowing agent for 95 the splints.

3. The process of treating match splints which consists in subjecting the splints to a bath comprising superimposed immiscible liquids of different specific gravity, one of the liquids being an organic flaming substance and the other a solution of a non-glowing substance.

4. The process of treating match splints

which consists in subjecting the splints to a bath comprising superimposed immiscible liquids of different specific gravity, one of the liquids being an oil and the other an 5 alcoholic solution of a non-glowing substance.

Signed at New York, in the county and

State of New York this 26th day of October
A. D. 1912.

WILLIAM A. FAIRBURN.
